UNITED STATES PATENT OFFICE.

THOMAS JEFFERSON BRUMBACK, OF CAPE GIRARDEAU, MISSOURI.

BUILDING WALL.

Application filed April 12, 1920. Serial No. 373,314.

To all whom it may concern:

Be it known that I, THOMAS JEFFERSON BRUMBACK, a citizen of the United States, and a resident of Cape Girardeau, in the 5 county of Cape Girardeau and State of Missouri, have invented certain new and useful Improvements in Building Walls, of which the following is a specification.

My invention relates to building walls, 10 floors and roofs, and the purpose of my invention is the provision of a building wall composed of a plurality of building units each of which is provided with tongues and grooves designed to receive the plaster material and to thus firmly secure the material to the units and to thereby secure the units to each other.

It is also a purpose of my invention to provide a wall, floor or roof construction in 20 which the building units above referred to are employed as laths sheathing or studding, in such manner that the plastic material used in forming any of these constructions is made to firmly secure one element to another 25 and to be reinforced by the units.

Another purpose of my invention is the provision of a building wall embodying my building units in both the inner and outer walls of a building in conjunction with a 30 concrete wall arranged between the two but contacting only with the outer wall so as to provide a dead air space for preventing the transmission of moisture through the building wall.

35 I will describe one form of building unit and one form of building wall, each embodying my invention, and will then point out the novel features thereof in claims.

In the accompanying drawings:

40 Figure 1 is a view showing in perspective one form of building unit embodying my invention.

Figure 2 is a perspective view of a portion 45 of a building wall embodying my invention and in which a plurality of building units shown in Figure 1 are employed.

Figure 3 is a vertical sectional view.

Figure 4 is a transverse sectional view.

Similar reference characters refer to similar parts in each of the several views.

Referring specifically to the drawings and particularly to Figure 1. A designates a building unit embodying my invention which is formed of a single length of wood 55 or other suitable material of rectangular formation, and is provided on each of its

longitudinal edges with a pair of tongues 15 and 15^a, and an intermediate tongue 16 between the two, all of such tongues being coextensive in length with the unit. The 60 tongues 15 and 15^a are tapered transversely from their point of connection with the unit to their outer edge, while the tongue 16 is formed with right angularly disposed faces. It will thus be seen that because of the contour of the tongues 15, 15^a and 16, longitudinally extending grooves 17 are formed which are substantially V-shaped in cross section, with the grooves at one side of the tongue 16 arranged in convergent relation with respect to the other groove. The outer edge of the tongue 16 is disposed beyond the outer edges of the tongues 15 and 15^a for a purpose which will be hereinafter described.

From the construction of the building unit 75 just described, it will be clear that when one unit is associated with a unit of like construction as shown in Figures 2 and 3, the tongues 16 on the confronting edges of any two units will contact with each other and 80 thus maintain the edges of the confronting tongues 15 and 15^a in spaced relation to each other so as to provide a dove-tailed channel 18 between each pair of tongues. Thus, a pair of dove-tailed channels 18 is provided 85 at the confronting edges of each pair of units with the grooves of each pair disposed upon opposite sides of the tongue 16.

Referring now to Figures 2, 3 and 4, I have here shown a building wall comprising 90 an inner wall W and an outer wall W'. The inner wall comprises a plurality of laths L which are constructed in accordance with the building unit shown in Figure 1 and are arranged one upon the other to provide the 95 dove-tailed channels 18. The laths L are nailed or otherwise secured to studs S arranged at intervals between the walls W and W' in the manner shown in Figure 2. As shown in Figure 3, each stud S is also constructed in accordance with the building unit shown in Figure 1. The remainder of the inner wall W is made up of layers of plaster P and P' applied to the opposite sides of the laths L. In the application of the plaster to the laths, portions of the former repose within the dove-tailed channels 18 so that when the plaster becomes hardened, each layer of plaster will be formed on its inner face with dove-tailed tongues 19 that 100 are securely locked within the grooves. As will be manifest, the tongues 15 and 15^a in-

terlock with the tongues 19 to firmly secure the layers of plaster upon the laths, while the plaster tongues 19 serve to reinforce the several laths, thus providing a wall of strong and durable construction.

The outer wall W' is also comprised of a plurality of laths, designated at L', arranged in superimposed relation in the same manner as the laths comprising the inner wall. The inner side of the laths L' are coated with a relatively thick layer of concrete designated at C, this layer being of such a width as to occupy approximately one half of the distance between the walls W and W' in order to provide a dead air space between the two. In the application of the concrete wall C to the laths L', it will be clear that portions of concrete will repose within the dove-tailed channels 18 of the laths to provide tongues in a manner similar to the tongues 19 of the layers of plaster P and P'. Similarly, these tongues serve to reinforce the laths, while the tongues 15 and 15^a of the laths serve to reinforce the concrete, this mutual reinforcement providing a wall of great strength. The dead air space between the two walls prevents the transmission of moisture from the outer wall to the inner wall so that the latter is maintained dry at all times. The outer surface of the laths L' may be covered with any suitable form of plastic material such as stucco, designated at T. This layer of plaster has portions thereof reposing within the dove-tailed laths L' thereby serving as an additional reinforcement for the laths L and the latter in turn securely retaining the plastic material thereupon.

As illustrated to advantage in Figure 4, the grooves 17 and 17^a of the stud S are so arranged as to receive portions of the plastic material comprising the layers P' and C so that when these materials become hardened they reinforce the studs, while the tongues of the latter provide an additional reinforcing means for the layers of plastic material.

From the foregoing description, taken in conjunction with the accompanying drawings, it will be manifest that I have provided a building unit of simple and efficient construction which is adapted for use as lathing and studding in the formation of a building wall. It is to be understood that the employment of a building unit as lathing and studding is only one adaptation of the invention as it may be used as sheathing or flooring in the construction of roofs and floors. It will be further manifest that I have provided a building wall of strong and durable construction in which all of the parts comprised in the wall coact to mutually reinforce each other, the dead air space provided between the walls preventing

the passage of moisture therethrough and thus maintaining the inner wall dry at all times.

It will also be manifest that by utilizing the units as lathing in either or both members of the wall that more perfect insulation as against heat or cold is obtained, as the wood lathing being a poor conductor of heat or cold prevents the passage through the wall wherein it is used to a greater extent than where no such lathing is used.

Although I have herein shown and described only one form of building unit and one form of building wall, each embodying my invention, it is to be understood that various changes and modifications may be made herein without departing from the spirit of the invention and the spirit and scope of the appended claims.

What I claim is:

1. A building wall, comprising inner and outer wall members of laths, said members spaced apart and connected by studs, said laths arranged one upon the other and formed with complementary undercut channels at their meeting edges, layers of plastic material disposed upon the opposite faces of the laths in their superposed arrangement, and having portions keyed within the undercut channels, the aforesaid studs arranged between the inner and outer wall members and having similarly shaped complementary undercut channels formed at their front and rear adapted to receive and key in portions of the plastic layers forming the inner spaced apart faces of the inner and outer wall members.

2. A building wall consisting of inner and outer members spaced apart, each member comprising laths superposed one upon the other and having complementary undercut channels at their meeting edges, layers of plastic material arranged upon opposite sides of the laths with portions thereof keyed within said channels, spacing studs disposed between the inner and outer members of the wall, and having similarly shaped complementary grooves or channels formed therein at front and rear for receiving and keying-in portions of the plastic material constituting the inner faces of the inner and outer wall members.

3. A building wall, comprising inner and outer spaced apart members, each member comprising laths superposed one upon the other, and layers of plastic keyed to the confronting faces of said inner and outer members, and undercut grooved spacing studs disposed between said members, and partially imbedded within the said plastic material, said studs reinforcing the confronting layers of plastic material.

THOMAS JEFFERSON BRUMBACK.
